ATTORNEY.

UNITED STATES PATENT OFFICE.

FORREST H. HODGE, OF LODI, OHIO.

OIL-PURIFYING APPARATUS.

Application filed March 6, 1926. Serial No. 92,694.

My invention relates to apparatus for purifying oil and particularly to apparatus of this character utilized in the oil fields for purifying crude petroleum. The objects of 5 the invention are to effect a satisfactory purification with simple and inexpensive apparatus that requires only a minimum of fuel for satisfactory operation.

The annexed drawings and the following 10 description set forth in detail certain means embodying my invention, such means constituting, however, only one of the several forms in which the principle of the invention may be embodied.

15 In said annexed drawings:

Figure 1 represents a side elevation of my improved oil-purifying apparatus, together with a broken elevation of a standard oil tank or reservoir;

20 Figure 2 is a vertical section, taken in the plane indicated by the line II—II, Figure 1; and

Figure 3 is an enlarged sectional view, taken in the area of Figure 1, indicated by 25 "A".

Referring to the annexed drawings in which the several elements are denoted by the same respective ordinals in the different views, I indicate a fire box by the ordinal 1 30 adapted to be heated by any suitable means available in the field where such apparatus is operated, the heating means herein being illustrated as a gas burner 2. If no gas is available, the fire box 1 might be heated by crude oil or any other available fuel. Welded to this fire box 1 and surrounding the latter, and spaced therefrom, as plainly shown in the accompanying drawing, is a jacket 3 which provides a space 3' utilized 35 for the water heating chamber, as herein-after fully described. Welded to the jacket 3, preferably respectively near the top and bottom of the same, the jacket 3 and fire box 1 preferably being set at a 45° angle, are 40 a pair of collars 4 and 5 communicating with a pair of nipples 6 and 7 respectively, which in turn communicate respectively with a pair of T's 8 and 9 respectively. The T 45 9 communicates with nipple 10 and also with nipple sections 16, 18, and 20 through the 50 medium of the check valve 15, a union 17,

and a stop cock 19, all as plainly shown in Figure 1. The other end of the nipple 20 is adapted to communicate with oil reservoir 21 intermediate the bottom of the reservoir 55 and the normal water line which is indicated by the ordinal 22. This oil reservoir is illustrated as of standard construction which would be normally about a hundred barrel oil tank. The T 8 communicates with an L 60 11, which in turn communicates with a nipple 12, and the latter in turn communicates with an L 13 which is contained within the upper end of the fire box 1, the nipple 12 intersecting the wall of the fire box, as 65 plainly shown in Figure 2. Telescopically arranged with the top of the fire box 1, is a pipe 23 adapted to serve as a smoke-stack, the top 1' of the fire box being bent into substantially a vertical position, as plainly 70 shown in Figure 2. The L 13 communicates with a stand-pipe 14 contained within the smoke-stack 23, and which at the top, through the medium of an L 24 and a bushing 25, communicates with a substantially 75 horizontally-arranged pipe 26 which is surrounded by a spaced jacket 27 and connects at its other end, through the medium of an L 28, with a depending pipe 29 of a length sufficient to reach below the oil line in the 80 tank 21.

For the purposes of illustration, I shall give some dimensions illustrating what the capacity of the different elements might be to give satisfactory operation. For instance, 85 the fire box 1 and jacket 3 might be 8 inches over-all diameter, of which the fire box is 5½ inches and the space 3' surrounding the same is 1½ inches. The collars 4 and 5 are 2 inch collars, the nipples 6, 7, 10, 12, 20, 90 etc., 2 inch nipples, the L's 13 and 24, 2 inch L's, the pipes 26, and 29, 1 inch pipes, the L 28, a 1 inch L, and pipe 14 and spaced pipe or jacket 27, 2 inch pipes.

It is well known to those skilled in the 95 art that water in crude petroleum filters to the bottom of the tank 21, as indicated by the water line 22. The purpose of the invention is to remove the impurities, such as fresh and salt water, foreign matters such as mud, etc., and this is accomplished by 100 heating the oil. The particular apparatus

which I have described and which is shown in the accompanying drawing, draws water from the bottom of the tank 21 and passes it to the chamber 3' where it is heated and passes up through the conduits 8, 11, 12, 14, etc., to the horizontal pipes 26 whence it passes into the oil and heats the same as it filters down to the water area indicated by the line 22. The arrangement of the water jacket 3 around the outside of the fire box 1 requires a comparatively small amount of fuel to effect this circulation of steam and water, ordinarily only about $\frac{1}{4}$ of the fuel necessary to effect the same result in apparatus with which I have previously been acquainted. This saving of fuel enables a simple and inexpensive heater to be used, which does the work of a large steam boiler in other apparatus with which I am acquainted, and is of particularly great importance when apparatus of this character is utilized in cold weather. The heating of the water, however, is not quick enough to precipitate the salt out of the oil before circulation has taken place. So soon as the burner 2 is shut off, it is possible to commence drawing off the purified oil through the outlet 31. The heavy impurities and the water are drawn off through the sludge drain 32.

I wish also to point out that the connections used for different parts of the apparatus can be of standard sizes and such as are commonly found in the outfits of oil well operators.

By means of continuing the nipple 12 into the stand-pipe 14 which passes up through the smoke-stack 23, I make use of the heat in the smoke-stack and thus utilize substantially all of the heat from the burner 2. By means of the jacket 27 surrounding the transfer pipe 26, I also protect the heated fluid from the cold and a further saving of heat is effected by extending the depending pipe 29 down below the surface of the oil in the tank 21, thereby making unnecessary the passage of the heated fluid through cold air.

The particular location of the upper transfer pipe 26, and the lower pipe, comprised of the nipples 10, 16, 18, and 20, is not limited to the exact location shown in the accompanying drawing but is flexible within the limits of having the upper pipe communicate with the tank 21 adjacent the upper oil line and having the lower pipe communicate with the oil tank 21 within the water area. Also, it would be perfectly feasible to utilize a plurality of these transfer pipes instead of limiting the same, as shown in the accompanying drawing, to one upper pipe and one lower pipe.

It will be perceived that two supporting legs 30 are connected with the jacket 3, which legs are adapted to co-operate with

the bottom of the burner 2 to form three supports for the smoke-stack and connected elements.

What I claim is:

1. Oil-purifying apparatus, comprising an oil reservoir, a fire box, a water jacket surrounding the directly heated portion of said fire-box, a pipe communicating at one end with the reservoir and at the other end with the lower end of the water jacket, a burner disposed within said fire-box, a smoke stack, a water stand pipe disposed entirely within the said stack, means for connecting the stand pipe with the upper end of said water jacket, and means connecting the upper end of the stand pipe within the stack and leading to and within the upper end of the reservoir.

2. Oil-purifying apparatus, comprising an oil reservoir, a heater connected with said reservoir, a water jacket surrounding the major portion of said heater, means connecting the lower portion of the reservoir with the lower end of the water jacket, a smoke stack connected with said heater, a water stand pipe disposed entirely within the smoke stack, a pipe connecting the lower end of the stand pipe with the upper end of the water jacket, and a pipe connecting the stand pipe within the stack with the upper end of the reservoir.

3. Oil-purifying apparatus, comprising an oil reservoir, a heater connected with said reservoir, a water jacket surrounding the major portion of said heater, a smoke stack, a pipe connecting the lower portion of the water jacket with the lower end of the reservoir, a water stand pipe disposed entirely within said stack, a pipe connecting the upper end of the water jacket with the lowermost end of the stand pipe, a horizontally disposed pipe connecting the stand pipe within the stack and leading to and within the oil at the upper end of said reservoir.

4. Oil-purifying apparatus, comprising an oil reservoir, a heater connected with said reservoir, a water jacket surrounding the major portion of said heater, a smoke stack connected with the heater, a vertical water stand pipe disposed entirely within said stack, a pipe connecting the lower end of the water jacket with the lower end of the reservoir, a pipe connecting the upper end of the water jacket with the lowermost end of the stand pipe, a pipe connected to the top of the stand pipe within the stack and leading to and within the top of the reservoir, and a jacket surrounding the pipe leading from the stack to said reservoir.

5. Oil-purifying apparatus, comprising an oil reservoir, an upwardly inclined supported heater connected with the reservoir, a water jacket surrounding the major portion of said heater, a smoke stack connected with the heater, a water stand pipe disposed

vertically entirely within the stack, a pipe connecting the lower end of the water jacket with the lower portion of the reservoir, a pipe connecting the upper end of the water jacket with the lower end of the stand pipe, a horizontally disposed pipe connected with the top of the stand pipe within the stack and leading to and within the oil in the upper end of the reservoir, and a spaced jacket surrounding said horizontally disposed pipe. 10
Signed by me this 13 day of February, 1926.

FORREST H. HODGE.
